UNITED STATES PATENT OFFICE.

HERBERT P. PEARSON, OF LONDON, ENGLAND, ASSIGNOR TO CRAVENETTE CO., U. S. A.,
A CORPORATION OF NEW JERSEY.

PROCESS FOR PROOFING HATS OF STRAW AND THE LIKE AND SAID PRODUCT.

1,197,304.

Specification of Letters Patent.

Patented Sept. 5, 1916.

Application filed January 15, 1912. Serial No. 671,258.

To all whom it may concern:

Be it known that I, HERBERT PINK PEARSON, a subject of the King of England, residing at 22 Basinghall street, London, E. C., 5 England, have invented certain new and useful Improvements in Processes for Proofing Hats of Straw and the like and Said Product, of which the following is a clear, full, and exact description.

10 This invention relates to the manufacture of hats of straw, chip (bast) and like materials and has for its particular object an improved method of finishing the same for the purpose of making them waterproof and 15 capable of being washed. In the manufacture of hats of this kind it is customary to soak the hat in an aqueous solution of gelatin and after drying, to shape it by pressure at a temperature at which the gelatin 20 is softened. The gelatin when the hat is dried imparts to the material of which the hat is composed the stiffness necessary to retain its shape and also gives it a smooth 25 finish. An objection to a hat of this character is that when it is exposed to rain, 30 water penetrates into and dissolves or softens the gelatin, causing the latter to swell so that the hat loses its shape and crispness. Attempts have been made to provide such 35 hats with a finish which is impervious to water and it has previously been proposed to treat them with a gum or collodion varnish for the purpose of making them waterproof. 40 A film of collodion or nitrocellulose protects the gelatin to a certain extent from the softening action of water, but it does not prevent water from clinging to the hat, which water will gradually soak through in spite of the film of nitro-cellulose. It has 45 also been proposed to render the gelatin insoluble in water by adding to the gelatin solution in which the hat is soaked formaldehyde or substances which liberate formaldehyde during the shaping operation. It has 50 been found however, that the use of formaldehyde-holding agents alters the gelatin in such a way as to make it gummy and rubber-like, so that difficulties occur in the shaping operations and the hat is not so crisp as it would be if treated with the ordinary gelatin solution alone.

In the present process, these prior disadvantages are avoided by treating a hat which has been previously stiffened and shaped by the aid of gelatin in the ordinary way, with 55 waxes or substances similar to waxes such as paraffin wax, ceresin wax, beeswax, carnauba wax, Japan wax, stearic acid, or stearin, all generically termed by me as "wax-like substances". These wax-like substances have the effect of preventing water from clinging to the hat and of causing rain drops to immediately run off. After the application of the wax-like substance, the 60 hat is preferably coated with an additional 65 waterproof varnish, which both assists in the shedding of the water from the hat and also protects the wax-like substance from the softening influence of the sun.

In the drawing, the figure is a conventional illustration of a straw hat, treated in accordance with the present invention.

H represents the hat soaked and stiffened in the usual gelatin solution.

A indicates the preliminary coating of 75 wax-like substance, and B indicates an outer film of a cellulose compound which acts like a varnish. It should be understood, however, that in an actual hat treated by this process the different coatings of wax-like 80 substance and nitro-cellulose compound, although preferably applied separately as hereinafter described, do not necessarily appear as separately applied layers in the resultant film. In other words, the line of demarcation between the separately applied 85 layers of wax-like substance and cellulose compound is not necessarily as clear as that illustrated in the drawing, and it might be hard to determine in the finished product 90 whether the waterproofed film upon a hat were made up of separately applied layers of wax-like substance and cellulose compound, or of one layer containing the wax-like substance and cellulose compound previously 95 mixed in some common solvent.

In carrying out the present process, the hat is first soaked in a suitable size such as a hot gelatin solution containing the usual bleaching materials, and is afterward shaped 100 by pressure and the application of heat in a manner now well known and practised in the

art. A hat thus prepared is then evenly coated with the wax-like substance, baked in an oven at a temperature above that at which the wax-like substance melts, so that it will be absorbed by the straw fiber of the hat. After cooling to a sufficient degree to allow the wax-like substance to harden, the hat is further treated with a waterproof varnish which may be any cellulose compound 10 which is soluble in acetone, such as, for instance, cellulose acetone, or cellulose ester, or nitro-cellulose, and the hat is then finally dried and finished.

The wax-like substance may be applied to 15 the hat in any convenient way;—for instance, the hat may be painted or sprayed with a solution of paraffin wax, or the wax-like substance while in a molten condition may be sprayed onto the hat, and the cellulose compound may be similarly applied by spraying it, while in solution, onto the hat. I have found that very satisfactory results are obtained by the use of paraffin wax melting at a temperature of approximately 54° 20 centigrade, but the other waxes above mentioned also give satisfaction. It is preferred for a straw hat of average size to employ about 6 drams of wax and about 35 drams of a nitro-cellulose solution, which, when 25 dried, leaves about 1½ drams of nitro-cellulose in the form of a film.

Although preferable, it is not absolutely necessary in the practice of this invention to apply the wax coating upon the hat prior 30 to the application of the cellulose compound, since fairly satisfactory results may be obtained by applying first the waterproof film of the cellulose compound, such as nitro-cellulose dissolved in acetone and then later 35 applying the wax thereto. It will be found in this manner of carrying out the process, that the wax will permeate more or less into the film of the cellulose compound and give the same a capacity for shedding water. The advantage, however, of applying 40 the wax coating first to the hat is that the cellulose compound film when afterward applied, protects the wax film more completely from the effects of the sun's rays.

45 Hats of straw and similar materials when treated in accordance with this invention are practically waterproof, and the effect of the wax-like substance is to prevent the water from clinging to the hat as it does to a hat which has been waterproofed with a nitro-cellulose varnish alone, and the hat retains the same stiffness as when finished with the gelatin size alone.

I wish it to be understood that the particular details of my process as heretofore 50 described, may be varied without departing from the spirit of my invention, and accordingly I desire to have the following claims broadly interpreted so as to cover the 55 full scope of my improvement.

What I claim is:

1. The process of waterproofing hats of straw and the like, which consists in applying thereto a surface coating of a wax-like substance so that the same is absorbed by 70 the straw fiber of the hat, and separately applying a surface coating of some cellulose compound which is characterized in acetone.

2. The process of waterproofing hats of straw and the like, which consists in applying 75 thereto a surface coating of a wax-like substance so that the same is absorbed by the straw fiber of the hat, and separately applying a surface coating of some cellulose compound which is characterized in acetone, 80 said wax-like substance being applied in larger quantity than said cellulose compound.

3. The process of waterproofing hats of straw and the like, which consists in applying 85 thereto a surface coating of a wax-like substance so that the same is absorbed by the straw fiber of the hat and separately applying a surface coating of a solution of nitro-cellulose. 90

4. The process of waterproofing straw hats and the like, which consists in first impregnating said straw with a solution of gelatin allowing the same to stiffen therein, and then applying thereto a surface coating 95 of a wax-like substance so that the same is absorbed by the straw fiber of the hat, and separately applying a surface coating of some cellulose compound which is characterized by its solubility in acetone. 100

5. As an article of manufacture, a straw hat having upon its outer surface a waterproofed film comprising a wax-like substance and some compound of cellulose which is characterized by its solubility in 105 acetone.

6. As an article of manufacture, a straw hat having upon its outer surface a waterproofed film comprising a wax-like substance and nitro-cellulose. 110

7. As an article of manufacture, a straw hat having upon its outer surface a waterproofed film comprising a wax-like substance and some compound of cellulose which is characterized by its solubility in 115 acetone, the quantity of the wax-like substance in said waterproofed film being greater than said cellulose compound.

8. As an article of manufacture, a straw hat having upon its outer surface a waterproofed film comprising a wax-like substance and some compound of cellulose which is characterized by its solubility in acetone, the approximate proportions being four parts of the wax-like substance to one 120 part of the cellulose compound.

9. As an article of manufacture, a straw hat impregnated with a gelatin size and having upon its outer surface a waterproofed film comprising a wax-like sub- 125

stance and some compound of cellulose which is characterized by its solubility in acetone, the quantity of the wax-like substance in said film being substantially 5 greater than the quantity of cellulose compound.

Signed at New York city, New York this
12th day of January, 1912.

HERBERT P. PEARSON.

Corrections in Letters Patent No. 1,197,304.

It is hereby certified that in Letters Patent No. 1,197,304, granted September 5, 1916, upon the application of Herbert P. Pearson, of London, England, for an improvement in "Processes for Proofing Hats of Straw and the like and Said Product," errors appear in the printed specification requiring correction as follows: Page 2, line 72, claim 1, same page, line 79, claim 2, before the word "cellulose" insert the word *dissolved*; same page, line 73, claim 1, and line 80, claim 2, after the word "characterize" insert the words *by its solubility*; and that the said Letters Patent should be read with these corrections therein that the same may conform to the record of the case in the Patent Office.

Signed and sealed this 3d day of October, A. D., 1916.

F. W. H. CLAY,

Acting Commissioner of Patents.
